UNITED STATES PATENT OFFICE.

OTTO LIEBKNECHT, OF FRANKFORT-ON-THE-MAIN, GERMANY, ASSIGNOR TO THE ROESSLER & HASSLACHER CHEMICAL COMPANY, OF NEW YORK, N. Y., A CORPORATION OF NEW YORK.

MANUFACTURE OF PERBORATES.

1,395,684.

Specification of Letters Patent.

Patented Nov. 1, 1921.

No Drawing.

Application filed January 27, 1917. Serial No. 145,017.

To all whom it may concern:

Be it known that I, OTTO LIEBKNECHT, a subject of the German Emperor and resident of Frankfort-on-the-Main, Germany, 5 have invented certain new and useful Improvements in the Manufacture of Perborates, of which the following is a specification.

It is known that alkali carbonates can be 10 converted by electrolysis into alkali percarbonates, and it is also known that alkali percarbonates can be again converted into alkali perborates (by double reaction) with borates.

15 In the matter of a prior application of the same inventor, it has been shown that the above known process can be successfully carried out in a single operation by subjecting a solution which, in addition to carbonate, 20 contains also borate, to electrolysis in the presence of solid perborate.

It is clear that in carrying out such processes on a manufacturing scale, the tendency should be to replace the expensive platinum 25 electrodes by a cheaper electrode material. Experiments which the inventor has carried out to that effect, have shown however that cathodes say of zinc, tin or aluminium which would at first sight appear to an expert very 30 suitable, cannot be used because they are attacked by electric atomizing or chemically by the electrolyte.

In experiments which the inventor made 35 with cathodes of such substances easily liable to destruction the surprising discovery was made that in the presence of certain substances, such as for instance chromic acid or chromates, the cathodes are not attacked, so that electrolytic manufacture of 40 perborates can be carried out without any disturbance. If for instance, tin is used as cathode material, a product will be always obtained which is colored gray by finely divided tin and is not very stable owing to 45 the presence of tin. If chromic acid is added to the electrolyte, a white product will be obtained which is free from tin and therefore stable, while at the same time the yield per unit of current will be improved 50 as the disturbing effect exercised by finely divided tin on the stability of the product is done away with. Chromic acid and chromates act in the same way when cathodes of zinc, aluminium, etc., are used.

On the basis of this discovery it is possible 55 to carry out electrolysis of perborates even with substances which under normal conditions are attacked during the electrolysis. Even when using cathodes which, like those of lead, iron, etc., possess already a comparatively good resistance to the action of the electrolytic liquid during electrolysis, it has been found advisable to make use of an addition of chromic acid or of chromates, for the stability of these substances is improved by the presence of such protective substances for the cathodes. In any case the presence of the protecting substances in question increases the life of the cathode, insures a smooth course of the electrolysis 70 with a better yield and gives a purely white end product free from metal.

Those parts of the cathodes which are not exposed to the current, are preferably protected from the action of the electrolytic 75 liquid—in as far as they are exposed to it—for instance by covering them with a resistant varnish or by securing to them pieces of substances which are not corroded, such as for instance vulcanized rubber.

80 The present process can be generally applied in the electrolytic manufacture of perborate. More particularly, it is not limited to the processes described in the prior patent-applications of the same inventor, 85 which are carried out in the presence of solid perborate, solid borax, solid soda.

I claim:

1. In electrolytic processes with a normally soluble base metal cathode, the step 90 which consists in adding to the electrolyte a protecting substance to stabilize the base metal cathode and prevent solution and deposition thereof in the end product.

2. In electrolytic processes with a normally soluble base metal cathode, the step 95 which consists in adding to the electrolyte a chromium-oxygen compound to stabilize the base metal cathode and prevent solution and deposition thereof in the end product. 100

3. In the electrolytic production of alkali perborate with a normally soluble base metal cathode, the step which consists in adding to the electrolyte a protecting substance to stabilize the base metal cathode 105 and prevent solution and deposition thereof in the product.

4. In the electrolytic production of

dium perborate with a normally soluble base metal cathode, the step which consists in adding to the electrolyte a chromium-oxygen compound to stabilize the base metal cathode and prevent solution and deposition thereof in the end product.

In testimony whereof I have signed my

name to this specification in the presence of two subscribing witnesses.

OTTO LIEBKNECHT.

Witnesses:

HARRY E. CARLSON,
JEAN GRUND.
